HOPPER DOOR REGULATOR

Edward J. Corrigan and Robert L. Wilson,
Calais, Maine

Application May 24, 1950, Serial No. 163,896

2 Claims. (Cl. 105—286)

1

This invention relates to a regulating device for regulating the opening of a hopper door beneath a freight car of the hopper body type.

An object of this invention is to provide an improved means whereby the hopper door of a freight car may be regulated as to its opening position so as to permit the discharge of the material from the interior of the car at a predetermined rate.

Another object of this invention is to provide a regulator of this type which is adapted to be secured to a rail and to engage the lower side of the hopper door with the regulator adjustable as to length so as to provide for opening or closing the hopper door to the desired degree.

Another object of this invention is to provide a regulator of this type which is separable from the hopper door and is of simple construction.

With the above and other objects in view, my invention consists in the arrangement, combination and details of construction disclosed in the drawings and specification, and then more particularly pointed out in the appended claims.

In the drawings:

Figure 1 is a detailed side elevation of hopper door regulator constructed according to an embodiment of this invention.

Figure 2 is a fragmentary longitudinal section taken on the line 2—2 of Figure 1.

Figure 3 is a transverse section taken on the line 3—3 of Figure 1.

Referring to the drawing, the numeral 10 designates generally the hopper body of a freight or railway car having a hinged hopper door 11 secured to the bottom wall 13 thereof. The hopper door 11 is adapted to be locked or latched in its upper closed position by any suitable locking or latching means (not shown), and in order to provide a means whereby the degree of downward swinging of hopper door 13 may be regulated, we have provided a screw jack 12 which is pivotally mounted on a rail clamping member 14. The rear end of the screw shaft 15 is flattened as indicated at 15, and the clamping member 14 which is formed of complementary vertically disposed webs 16 and 17 is formed with spaced apart ears 18 and 19 through which a pivot bolt 20 engages.

The bolt 20 engages through the flat end 15 of the screw shaft 12. The lower end of web 16 is formed with a U-shaped rail head clamping jaw 21, and the lower end of web 17 is formed of a U-shaped rail headed clamping jaw 22. The two U-shaped jaws 21 and 22 are tightly clamped to the rail head 23 by means of a clamping bolt 24. An elongated tubular member 25 telescopes over the forward end of the screw shaft 15 and is fixed at its rear end in a socket 26 formed in a nut 27 which is threaded on shaft 12. A handle or crank 28 is fixed to the

2

nut 27 and provides a means whereby the nut 27 may be rotated to extend or retract the tubular member 25. A door engaging head 28 is disposed at the forward end of the tubular member 25, being provided with a knurled forward end 29 and also including a stud 30. The stud 30 is rotatable in a bushing or sleeve 31 which is fixed as by pressing or the like in the forward end of tubular member 25.

10 A pair of thrust bearings 32 are interposed between the head 28 and the forward end of tubular member 25. The inner end of stud 30 may be upset as indicated at 33 so as to rotatably retain the stud 30 within bushing 31. The rear end of tubular member 25 is secured within socket 26 by means of a set screw or other fastening means 34.

15 In the use and operation of this regulator, when it is desired to drop door 11 to an open position, clamping member 14 is secured to the rail head 23, and swivel head 28 carried by extensible member 25 is adjusted by means of rotating the nut 27 to engage the lower side of door 11 and thereby hold this door in the desired open position.

20 This regulator will provide a simple means whereby hopper doors which are not regulatable by hand wheels or other means can be adjusted as to their open positions by a relatively finely adjustable means in the form of an extensible jack structure.

25 What is claimed is:

1. A regulator for the hopper door of a rail car comprising an extensible member formed of an elongated screw shaft and a tubular member 35 telescoping over said shaft, a nut fixed to said tubular member and threaded on said shaft, a handle fixed to said nut, a bushing secured in the forward end of said tubular member, a thrust bearing mounted forwardly of said bushing, a 40 stud extending through said thrust bearing and said bushing and freely rotatable therein, said stud having an upset rear end adjacent the rear end of the bushing for retaining said stud in said bushing, a door engaging head fixedly secured to the forward end of said stud and abutting against said thrust bearing, whereby said tubular member is rotatable relative to said head, the outer end of said head being knurled for holding the same in engagement with said hopper door, a vertically disposed clamp means for gripping a rail, and means pivotally mounting said shaft to said clamp means whereby said shaft and tubular member in the operative position thereof may be obliquely disposed relative to said clamp means.

2. A regulator for the hopper door of a rail car comprising an extensible member formed of an elongated screw shaft, a tubular member telescoping over said shaft, a nut fixed to said tubular member and threaded on said shaft, a handle

fixed to said nut, a serrated door engaging head rotatably carried by the forward end of said tubular member, a rail head clamp, and means pivotally securing the rear end of said shaft to said clamp, said extensible member when in operative position extending obliquely from said clamp.

EDWARD J. CORRIGAN.
